UNITED STATES PATENT OFFICE.

ROBERT MIEHLE, OF CHICAGO, ILLINOIS.

MECHANICAL MOVEMENT.

SPECIFICATION forming part of Letters Patent No. 317,663, dated May 12, 1885.

Application filed March 16, 1885. (No model.)

To all whom it may concern:

Be it known that I, ROBERT MIEHLE, a citizen of the United States, and a resident of the city of Chicago, in the county of Cook and State of Illinois, have invented certain new and useful Improvements in Mechanical Movements, of which the following is a specification, to wit:

This invention relates to improvements in that class of devices consisting of a pinion operating with a rack or racks to effect a reciprocating movement for printing-presses, pumps, iron-planers, large church-organ bellows, and other machinery wherein a regular reciprocating movement is desired between the centers, with a slow stopping and starting movement at the centers or turning-points of each reciprocating stroke.

The invention consists of a mechanism by which a very slow stopping and starting movement is obtained at each end of the reciprocating movement without losing the amount of stroke heretofore lost by diminishing the revolutions of the pinion, as will hereinafter be explained.

The invention also consists of a novel mechanism and arrangement of parts whereby the racks are shifted laterally of the pinion—that is to say, parallel with the axis thereof—to require less space in its operation; also, to obviate the necessity of a counter-balance when the pinion-shaft is placed in a horizontal position; and, furthermore, to obtain from a pair of racks and a pinion which has but one revolution a regular and complete reciprocating movement between its centers greater than the radius of the pinion or sweep of the wrist-pin across the centers, with a very slow stopping and starting movement at the end of each reciprocating stroke, the same as obtained from a crank-arm and wrist-pin.

It also consists of other combinations of parts, hereinafter described and claimed.

The device consists of two racks, a pinion, and wrist-pins for engaging automatically between end slots, to complete one reciprocating movement and advance on the succeeding one, and to alternately mesh the said racks with the pinion, as will hereinafter be described.

In the accompanying drawings, Figure 1 is a vertical side view of my invention, showing

the pinion, racks, and end shoes which form the end slots in their respective positions with the rack-frame. Fig. 2 is a vertical end view 55 of the same with the outer end shoe and a portion of the frame removed to which it is secured. Fig. 3 is a vertical side view, showing the wrist-pin as it is engaged between the end shoes at the time of leaving the racks. Fig. 60 4 is a view similar to Fig. 3, showing the wrist-pin at the point it begins to reduce the regular movement to turn its centers, with the pinion entirely disengaged from the racks. Fig. 5 is a vertical end view of a modified arrangement 65 of my invention. Fig. 6 is a vertical side view of the same. Figs. 7, 8, and 9 are views showing the arrangement of the wrist-pins on the pinion. Figs. 10, 11, and 12 are views showing the arrangements for taking 70 up all wear on the wrist-pins and the friction-rollers thereon. Fig. 13 is a diagram showing the driving distances usually obtained from pinions. Fig. 14 represents one of the bent pins which connect with the rock-75 arms for shifting the racks. Fig. 15 is a vertical side view of another modified arrangement of my invention. Fig. 16 is a vertical end view of the same with the outer end shoe and part of the frame removed 80 to which it is secured. Fig. 17 is a portion of Figs. 15 and 16 in a sectional plan view. Fig. 18 is a vertical side view showing one of the end slots so formed to have a quick stopping and a slow starting movement at the centers. 85

In reference to the drawings of the present invention, A represents the rack-frame, which is secured to the machine or device in almost any way it may be convenient or desirable, as the present improvement permits of the 90 pinion-shaft being put in a vertical as well as horizontal position.

The rack-frame A is provided with racks C C', with which the pinion D alternately meshes while operating in a continuous rotary motion. The racks C C' are positioned so as to permit of a lateral shifting movement of the pinion—that is to say, parallel with the axis of the pinion-shaft. The proper meshing of the said pinion and racks is obtained by the 100 wrist-pins E upon the pinion D, which automatically enters the slots E', (which are formed by the shoes A' A" at each end of the rack-frame A.) The wrist-pin E in passing through

the slots E' effects the gradual stopping of the one reciprocating movement and the gradual starting of the other, and also effects the lateral shifting of the racks C C', as will herein-
5 after be described.

In the constructions shown in Figs. 1 to 6 the parts are so proportioned that the pinion D makes two complete revolutions for reciprocating the rack-frame A and passes over both 10 centers, and when so proportioned two wrist-pins are necessary. Still I do not limit myself to such proportions. The pinion D may be made to take any number of revolutions for completing a reciprocating movement, as will 15 hereinafter be described.

I will now describe the lateral shifting of the racks.

In the rack-frame A is journaled a rock-shaft, Y, which has at each end arms F, which 20 extend outwardly and have slotted ends f', which connect with L-shaped pins c', as indicated in Figs. 1, 2, 3, 4, and 14, which slide loosely in the rack-frame A, and are secured to the racks C C', as indicated in Fig. 2.

25 Upon the rock-arms F are cams f f, as indicated in Figs. 1, 2, 5, and 6, which, as the wrist-pins E pass through the slots E', engage the outwardly-extending cam f, as indicated in Figs. 2 and 5, thereby imparting to the 30 rock-arms F through rock-shaft Y a swinging motion, by which the racks C C' and pins c' are shifted parallel with the axis of the pinion-shaft to properly mesh with the pinion D.

35 c" designates pins, which are secured into the rack-frame A. These pins are similar to pins c'. Their functions are to support the racks C C', wherein they fit loosely to allow the shifting thereof, heretofore described.

40 In Figs. 1, 2, 5, 6, 15, 16, and 17, D designates a face plate or rim secured upon the side of the pinion D, to prevent the racks C C' altering their positions while in operation with the pinion D.

45 In Fig. 5, g designates a spring secured to the rack-frame A, its function being to cushion the rock-arms F, and also to assist in starting the motion thereof as the wrist-pins E engage with the cams f f, as indicated in Figs. 50 2 and 5.

I do not limit myself to the use of the wrist-pin for shifting the racks, as other means may be employed, and the same may be held in their proper position by other means than 55 the face-plate D'.

Figs. 4 and 6 represent a slightly-modified form of the heretofore-described invention, in which the racks C C' are secured directly upon the rock-arms F. In this arrangement the 60 racks C C' are free to swing with the rock-arms F, and that portion of the frame in which pins c' c" are placed may be dispensed with and the shoes A' A" placed upon hangers A'', as indicated in Figs. 5 and 6. In this arrangement the face-plate D' may be dispensed with, as the pinion, when engaged with the

racks, will prevent the same altering their positions.

Figs. 15, 16, and 17 represent another modified arrangement of my invention, in which the 70 racks C C' and the end shoes, A' A'', are secured directly upon the rock-arms F, and the rock-shaft Y is journaled into hangers A''. In this arrangement the rock-arms F are shifted in just the opposite direction heretofore 75 described by a flange formed upon the friction-roller g' of the wrist-pin E, which engages into the grooves g' between the rock-arms F and the shoes A' A'', as indicated in Figs. 16 and 17 and in the dotted lines in Fig. 80 15. Fig. 15 also represents the parts proportioned and arranged so that the pinion will have but one revolution for completing a reciprocating movement.

By arranging the parts so that the pinion 85 has an odd number of revolutions—as one, three, and five—only one wrist-pin is required; but when the pinion has an even number of revolutions—as two, four, and six—two wrist-pins are necessary.

90 To take up the wear upon the friction-roller g' of the wrist-pins E, the shoes A' A'' are bolted upon flanges c of the rack-frame A, to allow an adjustment of the same by inserting any suitable packing between the shoes A' A'' 95 and flanges c, as indicated in Figs. 1, 3, 4, 6, 15, and 18, and to take up the wear upon the wrist-pin E and the inside of the friction-rollers g', which is necessary when a very smooth motion is desired, without any jar at the centers or turning-points. The shoes A' A'' are recessed one-half their bearing-surfaces, and the shoes A' have adjustable liners a fitted into the recesses, with set-bolts a' for adjusting the said liners, and bolts a'' for holding them in place, 100 as indicated in Figs. 10 and 11, and the friction-rollers g', made in two parts, as indicated in Fig. 12. It is evident that when the liner a is adjusted it presses the two halves of the friction-rollers g' around the wrist-pins E in such 105 a way as to make a close joint as it passes the centers, and when the whole width of the shoes is not necessary for the friction-roller g' to bear upon at the points at which they are curved the whole length of the shoes A' A'' 110 can be recessed. In this arrangement the one shoe is recessed on the inner side, nearest to the rack-frame A, and the other shoe on the outer side, so that the recessed parts of the shoes A' A'' do not face each other, as indicated in Fig. 12. The shoes arranged in this 115 way are adjusted the same as described for taking up the wear on the friction-roller. The liner a and bolts a' a'' are then dispensed with.

120 The taper pin f'', (indicated in Figs. 8 and 9,) inserted into the wrist-pin E and passing through the screw-head f''', is to prevent the screw f''' working out while the device is in motion.

125 The dotted lines I', which extend above and below the rack-frame A, as indicated in Figs.

90

115

120

125

130

1 and 6, indicate the points wherein the wrist-pins E complete the one and advance on the other epicycloidal curves, which they take up on the rack-frame A as the pinion D is meshing with the racks C C', and also indicate the distance traveled by the pinion D upon the racks C C' in exactly one-half revolution. It will evidently be seen that the wrist-pins E do not enter between the shoes A' A" until 10 they have passed the dotted lines I', and also that the larger the diameter of the friction-rollers g' upon the wrist-pins E the greater the space they will occupy in making the epicycloidal curves, and that by using a large friction-roller the time of entering the wrist-pins E between the shoes A' A" is delayed. The dotted lines I in Fig. 1 indicate the epicycloidal curves heretofore mentioned.

As it is very desirable to retain large friction-rollers upon the wrist-pins E, the delay just described is obviated by the axis of the wrist-pins being set somewhat below the pitch-line of the gears upon the pinion D, as indicated in Figs. 7, 8, and 9. The wrist-pins E, 25 when placed in such position, will pass the dotted lines I' with a quicker movement, whereby the friction-rollers g' upon the wrist-pins E are entered between the shoes A' A" at the same time as when the axis of the wrist-pins E are placed upon the pitch-line of the gear with small friction-rollers.

The wrist-pins E are formed with right-angled offsets or flanges g", which are fitted into recesses upon the side of the pinion D, as 35 shown in Figs. 7, 8, and 9. The lower flanges, which extend toward the axis of the pinion D, are bolted onto the web thereof, and on the upper flanges teeth are formed to correspond with those upon pinion D in place of 40 those cut away in forming the recesses. The rear ends of the wrist-pins E are formed with eccentrics g'", to allow sufficient metal to form and hold the teeth which are above the bore in the pinion D, through which the eccentrics 45 g''' are passed and bolted, as shown in Fig. 9.

The diagram Fig. 13 is to show the length of stroke obtained from pinions having two, three, and four revolutions, the large pinion being proportioned the same as pinion D in 50 the drawings, and the smaller one just one-half thereof. It is evident that when the revolutions of the pinions are diminished the length of the stroke is also diminished, the greater amount of stroke being lost when the 55 revolutions of the pinion are diminished from three to two revolutions for completing a reciprocating movement, and the length of stroke heretofore obtained from pinions, as shown in Fig. 13, is indicated by the dotted lines I" at 60 the pitch-lines of the gears, and the dotted lines I' at the end of that portion representing the racks. The manner in which the present improvement obtains a stroke greater than heretofore by a pinion with two revolutions is by the additional length of the racks 65 C C', which extend outwardly from the dotted

lines I', as indicated in Figs. 1 and 6, to enter the wrist-pins E between the end shoes, A' A", the ends of which are formed upon the epicycloidal curve I, heretofore described, sufficiently to receive the wrist-pins E properly 70 while the pinion is disengaging with either of the said racks, after which the shoes are shaped to impart a reduced movement to the rack-frame A by the wrist-pins E in time to 75 retain the slow stopping and starting motion at the centers or turning-points.

The shoes A' A" in the present drawings are formed in such manner as to produce a stroke—which is indicated by the dotted lines 80 I' at the end of the dotted lines I" in Fig. 6—with a pinion which has two revolutions to equal that obtained from the devices heretofore constructed, in which the driving circumference of the pinion is just one-half thereof, having four revolutions. It is evident the length of stroke can be extended by forming the shoes A' A" in the manner shown in Fig. 18, the upper half of which is formed upon the epicycloidal curves I very near to the center or 90 turning-point, the lower half of the shoes A' A" being formed the same as in the main drawings. By this arrangement a quick stopping or a slow starting movement at the centers or turning-points is imparted to the rack-frame A, and in turning the pinion in an opposite direction just the reverse movement is 95 obtained.

What I claim as my invention, and desire to 100 secure by Letters Patent, is—

1. In a mechanical movement, the combination of a rack-frame and racks with a pinion provided with a wrist-pin, which engages automatically into end slots, to properly guide the pinion with the said racks, substantially as 105 described.

2. In a mechanical movement, the combination of a rack-frame and racks, and a pinion provided with two wrist-pins, which engage automatically into end slots at each end with the 110 rack-frame, to properly guide the pinion to engage with the said racks, substantially as described.

3. In a mechanical movement, the combination, with a rack-frame, racks, and pinion, of 115 the racks having a lateral shifting movement imparted to the same in the direction of the axis of the pinion, to alternately engage the said racks with the said pinion, substantially as described.

4. In a mechanical movement, the combination of a rack-frame and racks, a pinion provided with a wrist-pin, and end shoes with the racks having a lateral shifting movement of 120 the pinion, substantially as described, and for 125 the purpose set forth.

5. In a mechanical movement, the combination of a rack-frame and racks, a pinion provided with a wrist-pin, and end shoes with the racks having a lateral shifting movement 130 imparted by the wrist-pin, substantially as described, and for the purpose set forth.

6. In a mechanical movement, the combination of a rack-frame and racks which shift laterally, a pinion, D, end slots, E', rock-arms F, and wrist-pin E, substantially as and for the purpose set forth.
7. In a mechanical movement, the combination of a rack-frame and racks which shift laterally, a pinion, D, end slots, E', and wrist-pin E, rock-shaft Y, rock-arms F, and cams f, substantially as and for the purpose set forth.
8. In a mechanical movement, the combination of a rack-frame and racks which shift laterally, a pinion, D, end slots, E', wrist-pin E, rock-shaft Y, rock-arms F, cams f, pins c' 15 c'', and face-plate D', all combined substantially as described.
9. In a mechanical movement, the combination of a pinion and wrist-pin, the wrist-pin having a right-angled offset with teeth formed thereon, substantially as described.
10. In a mechanical movement, the combination of a pinion and wrist-pin, the wrist-pin having right-angled offsets with teeth formed upon one of the said offsets and the other for 25 clamping to said pinion, substantially as described.
11. In a mechanical movement, substantially as described; the combination, with a pinion and wrist-pin, of the shoes A' A'', being adjustable, substantially as and for the purpose 30 set forth.
12. In a mechanical movement, substantially as described, the combination of a pinion and wrist-pin, made in two parts, with the shoes A' A'', being adjustable, the faces of which are 35 recessed or cut away, substantially as and for the purpose set forth.
13. In a mechanical movement, substantially as described, the combination, with a pinion and wrist-pin, the wrist-pin made in two parts, 40 of the shoes A' A'', being recessed, the shoes A' having adjustable liners with set-screws and bolts, substantially as and for the purpose set forth.

In testimony that I claim the foregoing as my 45 own I affix my signature in presence of two witnesses.

ROBERT MIEHLE.
